US0D1103970S

(12) United States Design Patent (10) Patent No.: US D1,103,970 S
(45) Date of Patent: * Dec. 2, 2025

(54) REMOTE CONTROL

(71) Applicant: Google LLC, Mountain View, CA (US)

(72) Inventors: Stefan Reichert, Mountain View, CA (US); Henry A. Beyer, San Francisco, CA (US); Maj Isabelle Olsson, Sunnyvale, CA (US); Katherine Morgenroth, Los Gatos, CA (US); Carl Cepress, Los Altos, CA (US); Diana Chang, San Jose, CA (US)

(73) Assignee: Google LLC, Mountain View, CA (US)

() Term: 15 Years

(21) Appl. No.: 29/883,170

(22) Filed: Jan. 25, 2023

Related U.S. Application Data

(63) Continuation of application No. 29/825,757, filed on Feb. 4, 2022, now Pat. No. Des. 980,193, which is a continuation of application No. 29/737,188, filed on Jun. 5, 2020, now Pat. No. Des. 955,366.

(57) CLAIM

The ornamental design for a remote control as shown and described.

DESCRIPTION

FIG. 1 is a front perspective view of a remote control showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 5 Drawing Sheets
